ATTORNEY

UNITED STATES PATENT OFFICE

CHARLES E. JOHNSON, OF NEW YORK, N. Y.

KITCHENETTE AND MEDICINE CABINET

Application filed March 30, 1929. Serial No. 351,335.

This invention relates generally to display devices and has more particular reference to a novel kitchenette and display cabinet especially adapted to hold medicines and the like, small kitchen utensils, or for displaying novelties such as watches, jewelry or other small objects, or for storing dishes.

The invention has for an object the provision of a device of the class mentioned, which is of simple durable construction, desirable in use and efficient in action, and which can be manufactured and sold at a reasonable cost.

The invention proposes the use of a frame having a flat rear, sides extending forward therefrom and parallelly arranged, and supplementary sides integral with the front edges of the said sides and extending rearwards along the inner sides of the said sides. Racks are supported between these supplementary sides and slideable covers and doors are arranged for closing the device.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a front elevational view of a device constructed according to this invention.

Fig. 2 is a fragmentary plan view thereof.

Fig. 3 is a fragmentary sectional view, taken on the line 3—3 of Fig. 1.

Fig. 4 is a vertical sectional view, taken on the line 4—4 of Fig. 1.

Fig. 5 is an enlarged view of the lower left hand corner of Fig. 1 disclosing a modified form of the device.

Fig. 6 is a sectional view, taken on the line 6—6 of Fig. 5.

Fig. 7 is a side elevational view of the device when used as a dish drainer.

Fig. 8 is a plan view of the device constructed according to modified form.

Fig. 9 is a side view thereof.

Fig. 10 is a transverse vertical sectional view of the device as seen in Fig. 9.

Fig. 11 is a longitudinal vertical sectional view of the device as seen in Fig. 9.

The device is provided with a frame having a flat rear 10, parallel forward extending sides 11 integral with the rear, supplementary sides 12 integral with the front edges of the said sides 11 and extending rearwards on the inner sides thereof, top flanges 13 extending inwards from the said rear and the said forward extending sides, bottom flanges 14 extending inwards from the said rear and the said forward extending sides, and the said supplementary sides 12 being of smaller height than the said sides 11 so as to provide grooves 15 between the edges of the supplementary sides and the top and bottom flanges. A plate of glass 16 is slidably engaged in the top groove 15 and a second plate 17 is engaged in the bottom groove 15.

The rear edges of the supplementary sides 12 are bent inwards and rearwards to form end flanges 18. A top display bracket 19 is provided with side flanges 20 pivotally mounted on the end flanges 18 as indicated by numeral 21. This top display bracket has one face covered with felt 22 and is provided with an enlarged bottom 23. A bottom display bracket 24 is also provided with end flanges 25 pivotally mounted on the end flanges 18 as indicated by numeral 26. This bottom display bracket is provided with an enlarged bottom 27 and intermediate display rack 28.

Connector rods 29 are each pivotally mounted at one end upon the enlarged bottom 23 of the top display bracket and at its other end on the enlarged bottom 27 of the bottom display bracket. Links 30 are each pivotally mounted on one of their ends on the end flanges 18 and are provided with wing screws 31 on their upper ends engaging in slots 32 formed in the connector rods 29. The arrangement should be such that the end of the links 30 may be fixed in any desired position in the slots 32.

A plurality of display rods 33 are mounted between the said end flanges and are removably arranged by reason of one of the ends of each rod engaging in a slot 34 in the said end flanges. Several top guide rods

35 are mounted between the supplementary sides 12 and similar bottom guide rods 36 are also mounted between the supplementary sides to form guides for sliding doors 37 and 38. These sliding doors are made from glass and each door is shown mounted between different guide rods 35, 36. A window frame 39 is arranged upon the front face of the said flat rear 10 and supports a glass window 40 disposed over an opening 41 in the said flat rear 10. This adds to the value of the case in that articles arranged on the racks may be viewed from both sides. A support bar 42 is of U-shape and has its side arms 15 pivotally mounted on the sides 11, and extends behind the said flat rear 10.

In the modified form of the device illustrated in Figs. 5 and 6, a wooden base 43 has been shown provided with a groove 44 for receiving the bottom flanges 14 so that this wooden base may be slidably engaged upon the frame. When this wooden base is used the glass 17 is eliminated from use. Transverse grooves 45 are formed in this wooden base for receiving the lower edges of the doors 37 and 38 for guiding these doors in their sliding movements. One tie rod 46 is connected between the said supplementary sides 12 for strengthening and holding these sides in proper condition. Weatherstrips 18^a are attached on the said flanges 18 for coacting with the doors 37 and 38 in closed positions.

In operation of the device the doors 37, 38 35 may be moved to an open position and articles placed upon the display rods 33 or upon the display brackets 19 and 24. In the event that the device is to be used in a kitchen for supporting plates or the like, the top and bottom glass plates 16 and 17 respectively 40 may be removed from the frame and then the doors 37 and 38 may also be removed. The device may then be placed with the flat rear side resting upon a table with the sides 45 11 extending upwards and plates or the like may be engaged between the rods 33 and thus supported in partially raised position.

In Fig. 7 the device is shown with the support rod 42 resting upon a table for supporting the device in a slightly inclined position so that water from wet plates may drain off. The device shown in this figure is further modified by one of the flanges indicated by reference numeral 15^a being turned downwards to form a drain edge.

In the modified form of the device illustrated in Figs. 8 to 11 inclusive a frame 47 has been shown having a flat bottom 48, parallel upward extending sides 49 integral with the bottom, supplementary sides 50 integral with the top edges of said sides and extending downwards on the inner sides thereof, and the longitudinal free edges 51 of the supplementary sides are bent towards each other

to form guides for a slide 52. The slide 52 consists of parallel bars 53 held in spaced relation by spaced rungs 54. The top ends of the sides 49 and 50 are held in spaced relation by spacers 55. Handles 56 are pivotally mounted on the ends of the frame. The flat bottom 48 of the frame has down turned ends 57 and reinforcement rods 58 are connected between these ends.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A device of the class described, comprising a frame having a flat rear, parallel forwardly extending sides integral with the rear, supplementary sides integral with the front edges of said sides and extending rearwards on the inner sides thereof, and top and bottom flanges extending inwards from the said rear and the forwardly extending sides and arranged for forming grooves to receive glass plates in cooperation with the ends of the supplementary sides, glass plates engaged in the grooves, display racks supported by the supplementary sides, and glass doors for sliding across the front ends of the forwardly extending sides.

2. A device of the class described, comprising a frame having a flat rear, parallel forwardly extending sides integral with the rear, supplementary sides integral with the front edges of said sides and extending rearwards on the inner sides thereof, and top and bottom flanges extending inwards from the said rear and the forwardly extending sides and arranged for forming grooves to receive glass plates in cooperation with the ends of the supplementary sides, glass plates engaged in the grooves, display racks supported by the supplementary sides, and arranged for assuming various fixed positions, and glass doors for sliding across the front ends of the forwardly extending sides.

3. A device of the class described, comprising a frame having a flat rear, parallel forwardly extending sides integral with the rear, supplementary sides integral with the front edges of said sides and extending rearwards on the inner sides thereof, and top and bottom flanges extending inwards from the said rear and the forwardly extending sides and arranged for forming grooves to receive glass plates in cooperation with the ends of the supplementary sides, glass plates engaged in the grooves, display racks supported by the supplementary sides, and arranged for assuming various fixed positions, and glass doors for sliding across the front ends of the

forwardly extending sides, guided between rods extending between the supplementary sides.

4. A device of the class described, comprising a frame having a flat rear, parallel forwardly extending sides integral with the rear, supplementary sides integral with the front edges of said sides and extending rearwards on the inner sides thereof, and top and bottom flanges extending inwards from the said rear and the forwardly extending sides and arranged for forming grooves to receive glass plates in cooperation with the ends of the supplementary sides, glass plates engaged in the grooves, display racks and rods supported by the supplementary sides, and glass doors for sliding across the front ends of the forwardly extending sides.

5. A device of the class described, comprising a frame having a flat rear, parallel forwardly extending sides integral with the rear, supplementary sides integral with the front edges of said sides and extending rearwards on the inner sides thereof, and top and bottom flanges extending inwards from the said rear and the forwardly extending sides and arranged for forming grooves to receive glass plates in cooperation with the ends of the supplementary sides, glass plates engaged in the grooves, display racks supported by the supplementary sides, a support bar pivotally attached on the first mentioned sides and extending across the said flat rear, and glass doors for sliding across the front ends of the forwardly extending sides.

In testimony whereof I have affixed my signature.

CHARLES E. JOHNSON.
